(57) **CLAIM**

The ornamental design for a glowing display accessory for automobile, as shown and described.

DESCRIPTION

FIG. 1 is a front perspective view of a glowing display accessory for automobile in accordance with the design;
FIG. 2 is a front elevation view thereof;
FIG. 3 is a rear elevation view thereof;
FIG. 4 is a right-side view thereof;
FIG. 5 is a left-side view thereof;
FIG. 6 is a top view thereof; and,
FIG. 7 is a bottom view thereof.

The broken lines present in the drawings are for illustrative purposes only and form no part of the claimed design.
